DISHWASHING MACHINE

Harold G. Davis, Denver, Colo.

Application July 28, 1932, Serial No. 627,611

16 Claims. (Cl. 141—9)

This invention relates to a dishwashing machine, and has for its principal object the provision of a neat, compact, portable dishwashing machine which will have a maximum dish capacity and which will efficiently wash and dry the dishes.

Other objects of the invention are:—To so construct the washer that it will have a relatively low vertical height so that it can be used upon the usual kitchen sink drain board and yet be convenient for the placement of the dishes and so that it will discharge its contents directly into the sink;

To increase the dish capacity and the washing effect by employing a relatively long, rectangular tank with an eccentrically positioned impeller;

To prevent the incoming water from directly striking the dishes so as to prevent breakage from temperature expansion;

To provide means for supplying a cooling draft to the driving motor during the washing operation, and for heating and diverting this draft into the dish chamber during the drying operation to evaporate and carry off the excess moisture;

To construct the machine with a sump in which all of the solid particles from the dishes will collect and from which these solid particles can be instantly discharged and the sump flushed;

To provide a fan or blower rotor which will also serve as a belt pulley;

To provide an efficient and automatic device for keeping the belt taut and accommodating for wear therein;

To provide means which will prevent the operator from turning water into the dish chamber during the drying operation so as to avoid injury to the motor, electric connections, or heater.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a plan view of the improved dishwasher 50 with the lid partially broken away to illustrate the interior construction.

Fig. 2 is a similarly broken away view illustrating a side elevation of the dishwashing machine and the position of the dishes therein.

Fig. 3 is an end elevation thereof.

Fig. 4 is a vertical section taken on the line 4—4, Fig. 2.

Fig. 5 is a detail section taken on the line 5—5, Fig. 8.

Fig. 6 is a detail plan view of the combined belt pulley and fan rotor.

Fig. 7 is a detail section through the sump taken on the line 7—7, Fig. 1.

Fig. 8 is an enlarged section through the operating mechanism taken on the line 8—8, Fig. 3, 10

Fig. 9 is a diagram of the electric circuits of the machine.

Fig. 10 is a section similar to Fig. 8, illustrating an alternate arrangement of the operating parts.

Fig. 11 is a detail view illustrating the lid 15 clamping handle.

For the sake of clearness, the dish racks and guards are omitted from all views except Fig. 2.

Construction

The dishes are received on suitable racks 66, conveniently arranged within a washing tank 10. The tank 10 is supported on legs 10'. It is preferred, but not necessary, to have the forward legs of slightly greater height than the rear legs 25 in order to maintain the tank 10 level in the usual inclined sink board, as shown in Fig. 2.

It is desired to call attention to the fact that the tank 10 is formed with rectangularly positioned parallel side walls, and is of oblong shape. 30 The arrangement of the side walls, and the shape of the tank are very important for several reasons. The water will be reflected from the flat walls and will splash across the corners from one wall to another creating a maximum agitation 35 that is impossible in a round tank; the dishes will stack with less waste space in a rectangular tank than in a round one; and this particular oblong rectangular shape corresponds to the shape of the usual sink drain board upon which the machine is 40 designed to be placed.

The tank 10 is covered by means of a removable lid 11 which may, if desired, be provided with a plate glass top 12 to allow the operator to view the progress of the washing. A peripheral 45 packing groove 13 is formed about the lid 12 to receive suitable sealing packing, and to receive the upper edge of the tank 10. The lid 11 is provided at its extremities with hinged handles 14 from which depend spring wire clamping loops 50 15 arranged to engage under lips 16 formed on the tank 10. It will be noted that as the handles 14 are swung downwardly toward the dotted line position of Fig. 2, they will act to tighten the clamping loops 15 so as to clamp the lid 11 down- 55

wardly upon the container 10 until a perfect seal is obtained. Pins 82 are arranged to kick the loops 15 outward as handles are swung upward.

The bottom of the tank 10 is slightly hopper shaped. An impeller 17 is positioned above the lowest point of the bottom. In use the dishes are protected from the impeller by means of wire netting guard 81. It is desired to call attention to the fact the position of the impeller is eccentric 10 of the tank 10, that is, it is positioned upon the longitudinal center line but relatively closer to one extremity than the other. This allows the machine to be sufficiently reduced in size to be placed upon the ordinary sink board and yet allows the larger plates to be placed directly at the side of the impeller so that they will receive the direct side throw of the water. If the impeller were centrally positioned, as is usual in dishwashing machines, the length of the tank would need 20 to be increased in order to place plates alongside of the impeller or the capacity would be materially reduced in order to position the plates above the impeller. It also positions the tank irregularly about the impeller so that the water thrown by the impeller will strike the dishes at an infinitely great number of different angles so as to reach all irregular surfaces thereon.

From the low point of the bottom of the tank 10, a depressed channel 18 leads to what might be termed a sump tube 19, into which all of the heavy insoluble substances washed from the dishes will gravitate so as to be out of the range of action of the impeller 17. The sump tube 19 is closed by means of a sump plug 20, the operation of which will be later described.

The tank is filled through a flexible hose 21, which leads to a suitable connector 22, by means of which it can be attached to the sink faucet outlet. Suitable clips 23 are provided on the tank 35 40 10 for supporting the hose 21 when not in use.

It is desired to call attention to the fact that the hose 21 discharges through an inlet nipple 24 in the sump tube 19 and that the incoming jet is directed longitudinally of the sump 19 toward 45 the outlet. This particular construction is important. It provides a jet of water which will wash the solid substances from the sump tube when the plug 20 is removed; when the plug 20 is in place, it provides a baffle chamber to receive 50 the incoming jet of water so that it will not be projected directly against the dishes, which might result in damage, should the water be exceedingly hot; and it prevents any water from being accidentally introduced into the tank 10 during 55 the drying operation, for should the water be turned on while the machine is operating as a dryer, the incoming jet of water will be projected straight through the outlet without allowing it to enter the tank 10.

60 A motor chamber 25 is indented into the forward extremity of the tank 10. The outer face of the motor chamber is closed by means of a motor plate 26 which is secured to the tank by means of suitable cap screws 27. The motor plate 26 supports the entire driving mechanism as well as the heating and valve structures so that all the operating parts, with the exception of the impeller 17, can be removed for inspection or repair by simply removing the cap screws 27.

70 A U-shaped motor yoke 28 is secured to the inner face of the motor plate 26 and provides a horizontal slide support for an electric motor 29. The lower extremity of the shaft of the motor 29 is provided with a suitable belt pulley 30 for re-

ceiving a driving belt 31 for driving the impeller 17.

A detail construction for the impeller and its driving mechanism is illustrated in the applicant's co-pending application, Serial No. 604,233, which has matured into Patent No. 1,934,970, granted November 14, 1933. Briefly, the impeller is driven by a flexible shaft 32 which extends through a rotatable bearing bushing 33 which acts to offset the axis of the impeller so that it will oscillate 10 in an orbit as well as rotate. The bearing bushing 33 carries an arm 34 which terminates in a deflector vane 35 above the impeller. The rising jet of water from the impeller blades will strike the deflector vane so as to cause it to rotate the 15 arm 34 and the bearing bushing 33. This causes the axis of the upper portion of the impeller to constantly swing in an orbit about the vertical so as to direct the jet of water at constantly varying angles as described in the said co-pending 20 application.

It is desired to call attention to the combined belt pulley and fan which is carried on the lower extremity of the flexible shaft 32. It comprises: a belt pulley 36 for receiving the drive belt 31 with 25 vanes 37 projecting from both sides of the belt pulley 36 to act as a centrifugal fan.

The yoke 28 is inset in the sides of the motor which is held in place by cross bars 40 extending over the sides of the yoke so that the motor is free 30 to slide horizontally thereon. It is constantly urged, however, toward the left so as to maintain the belt 31 at the proper tension by means of two eccentrics 38. The eccentrics 38 are mounted on the yoke 28 and provided with springs 39 which 35 tend to rotate them forwardly so that they will bear against the cross bars 40 of the motor. Handles 41 are provided on the eccentrics so that they may be reversed to loosen the belt 31 should it be desired to remove the latter. This particular construction has been found to be highly efficient and no attention whatever has been required to insure the proper tension in the belt 31. As the belt 31 wears, the vibration of the motor, together with the action of the springs 39, will 40 constantly move it toward the left to take up any looseness in the belt.

45 The motor plate 26 is provided with an outer air discharge port 42 adapted to be closed by means of an outer air valve 43. The motor chamber 50 25 is provided with an inner air discharge port 44 closed by an inner air valve 45. The two air valves 43 and 45 are mounted on the extremities of a common valve stem 46 which is guided by a valve stem guide 47 extending inwardly from the motor plate 26 and provided with a chamber for a valve spring 48. The action of the spring 48 is to normally maintain the inner valve 45 closed, and the outer valve 43 open.

55 A tube of refractory material surrounds the 60 valve stem guide 47 in spaced relation thereto, and supports a coil of suitable resistance wire to form a heating element 49. The heating element is supported upon the upper extremity of the frame of the motor 29 so that it is removable 65 as an integral part thereof. The bottom of the motor chamber 25 and the belt and its pulleys are enclosed by a hood 50. The hood 50 is removably secured in place by a rubber pad 51 which serves as a fifth leg for the machine, and 70 which is threaded upon a downwardly projecting stud 52 from the tank bottom. The hood 50 is provided with suitable air intake openings 53 adjacent the fan blades 37.

75 The sump plug 20 is carried upon the extremity 75

of a plug arm 54 which passes through what will be termed a cam box 55. Within the cam box 55 the plug arm 54 carries a cam 56 against which a spring yoke 57 is constantly urged by means of a pair of yoke springs 58. On the opposite side of the cam box 55, the plug arm 54 is provided with an operating handle 59 terminating in a hand ball 60.

When the hand ball 60 is in the bottom position of Fig. 8, the springs 58 will be acting against the cam 56 to cause the plug arm 54 to press the sump plug 20 inwardly to close the sump tube 19. When the ball is in the upper position, or broken line position of Fig. 8, the springs 58 will be pressing the spring yoke 57 against the cam 56 so as to cause the ball 60 to press the outer air valve 43 closed and fully open the inner air valve 45.

When the operating handle 59 is in the bottom position, it will depress an electric switch button 61 which will act to shut off the supply of electricity to the heating element 49. The supply of current for the motor 29 is controlled by means of a control switch 62. A typical electrical hook-up is indicated in the diagram of Fig. 9. The proper depth for the water in the tank 10 is determined by means of an overflow tube 63.

Operation

The machine is placed upon a sink board or other suitable support having convenient electric supply and drainage facilities. The hose connector 22 is connected to the sink faucets. The dishes are placed in the racks 66, and the operating handle 59 is swung downwardly to cause the plug 20 to close the sump tube 19. If necessary, suitable soap is placed in the machine. Hot water is then turned into the hose 21 to fill the sump tube 19 and rise in the tank 10 until it starts to overflow through the overflow tube 63. The water is then shut off, and the switch 62 is turned on to start the motor. The motor will rotate the impeller 17 and direct a jet of water upwardly and outwardly in a constantly oscillating sheet through the dishes.

When the dishes are cleaned, the operator lifts the hand ball 60 to open the sump plug 20 and allow the dirty water to discharge from the sump tube 19 to the sink. He then releases the ball 60 to allow the springs 58 to close the sump plug 20 and turns a supply of rinsing water to the machine. When the dishes are sufficiently rinsed, the ball is again lifted to discharge the rinse water through the sump tube 19.

During the washing and rinsing operations, air is drawn through the air intake openings 53 in the hood 50 by the action of the fan blades 31. This air is forced upwardly through and past the motor 29 to effectively cool the same, and is discharged through the outer air discharge port 42 to the atmosphere. The heating element 49 is not in operation at this time since the electric button 61 is depressed by the handle 59 to cut off the current supply thereto. Thus an efficient air cooling system is provided for the motor which prevents it from over-heating even during long periods of operation.

After the rinsing has been completed, the operator lifts the ball 60, allowing the cam 56 to pass the dead center position against the spring yoke 57, so that the springs 58 will act to press the ball against the outer valve 43, closing it, and opening the inner valve 45. The upward movement of the handle 59 has, of course, released the electric button 61 so that the heating ele-

ment 49 will start to operate to create an intense heat in the upper part of the motor compartment 25.

The fan blades will now operate to draw in a current of fresh air and pass it upwardly into the motor chamber, slightly compressing it in the heated upper portion thereof in and around the heating element 49. The air will become heated to a comparatively high degree before it is released into the interior of the tank 10 through the inner air port 44. This hot air will be forced in and around the dishes in intimate contact therewith by the action of the impeller 17 so as to quickly evaporate any remaining water thereon, and leave them in a dry, clean, sanitary condition. The humid air carrying away the moisture from the dishes discharges through the sump tube 19.

It is desired to call attention to the fact that the motor and heating elements are sealed from the tank 10 during the washing operation, but are exposed thereto during the drying operation. The machine is so arranged, however, that it is practically impossible to accidentally allow water to enter the tank, during the drying operation, which might damage the operating and heating mechanisms. First the novel position of the water nipple 24 in the sump tube 19 allows the incoming water to discharge immediately without entering the tank; second, the sump plug 30 must always be open before the inside valve 45 can be opened because of the co-acting action of the operating handle 59; and third, the comparatively large diameter of the sump tube 19 allows the water to discharge from the tank almost immediately so that it would be exceedingly difficult to swing the handle 59 upwardly quickly enough to operate the inner valve 45 before the water had discharged from the tank.

If it is desired, however, to absolutely eliminate this possibility, a mechanism such as below described, may be employed. It comprises a locking lever 68 having a bifurcated extremity 69 which will receive the operating handle 59 as it is swung upwardly and prevent it from contacting 45 with the outer valve 43. Then in order to close the outer valve 43 and open the inner valve 45, it is necessary for the operator to rotate a knurled, headed screw 70. The screw moves a nut 71 therealong to actuate the locking lever 68 51 and cause its bifurcated extremity to allow the operating handle 59 to move inwardly to a contact with the outer valve 43. This mechanism thus acts to delay the opening of the inner valve 45 until it is certain that all of the water will 55 have drained from the tank 10. It is desired to call attention to the fact that the lever 68 locks the operating handle 59, as shown in Fig. 5, to prevent operation thereof to close the sump valve until the screw 70 has first been rotated to simultaneously release the handle 59 and permit the outer valve 43 to open, and the inner valve 45 to close.

Alternate form

There are, of course, other arrangements possible for the air blower and heating elements which would still accomplish the essential feature of this invention; that is, the combining in a single machine of a washing and drying action. One of these alternate arrangements is illustrated in Fig. 10, in which, the position and construction of the heating element and fan are changed from that previously described.

In this form the shaft of the operating motor 75

is extended upwardly, as shown at 17, and terminates in a fan or blower 72. The blades of the blower extend downwardly about a cylindrical heating element 78. The heating element 78 is carried on a hollow cylindrical refractory tube surrounding the upper extremity 17 of the motor shaft. The operation of this form is similar to that of the previously described form, that is, during the washing operation, air is drawn through the motor by the action of the blower 72 and discharged through the outer air valve. During the drying operation, air is drawn through the motor and around the heating element 78, and is then discharged through the inner air valve. It is preferred to position a blower plate 73, provided with intake air openings 74, immediately below the blower so as to guide the incoming air toward the axis of the blower rotor into intimate contact with the heating element 78. In this form, a simple belt pulley 75 is employed in place of the combined belt pulley and fan of the previously described form.

The current of the motor is supplied through a suitable electric cord 64, suitable winding clips 65 being provided on the tank 10 to receive the cord 64 when not in use. The tank is provided with suitable carrying handles 67 by means of which it may be easily lifted to place. The noise of the motor 29 is absorbed by means of a rubber pad 68 positioned between the yoke 28 and the motor plate 26. The particular mounting of the motor also serves to reduce noise and vibration, for should there be any looseness between the motor and its yoke 28, it will be absorbed by the resilient action of the eccentrics 38 which serve to clamp the motor and prevent rattling.

It has been found that drops of water will hang from the dishes after the washing operation which materially increase the time necessary to dry them. It has also been found that a slight vibration will loosen these drops so that they will either fall from the dishes or spread over the surface thereof to facilitate the drying operation. One method of imparting this vibration is to form a weight boss, such as indicated at 19 on the belt pulley 36. This boss is not sufficiently heavy to cause any noticeable vibration during the washing operation, since the resistance of the water retards the speed of the pulley 36 to a considerable extent. During the drying operation, however, the speed of the pulley 36 materially increases so that the eccentric position of the boss causes it to rapidly vibrate the entire machine. This loosens and distributes the drops of water and facilitates the drying operation. It will be noted that the legs 10' are provided with rubber cushions 80 which serve to absorb this vibration.

The fifth leg formed by the rubber pad 51 can be used to support the forward extremity of the machine on short drain boards on which the two forward legs 10' would project over the sink.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:—

1. A dishwashing machine of the type having a tank and a motor driven impeller therein; means operable by said motor for creating an air draft; and a valve arranged to admit said air

draft to said tank when desired; and a second valve arranged to operate in unison with said first valve so that said air draft will be discharged to the exterior of said tank when said valves are in one position, and to the interior of said tank when said valves are in another position.

2. A dishwashing machine comprising: a tank; means for supporting dishes in said tank; a motor compartment in one extremity of said tank; a vertically mounted motor in said motor compartment having a motor shaft extending upwardly and downwardly therefrom; an impeller in said tank; an impeller shaft extending from said impeller through the bottom of said tank; means for transmitting power from the downwardly extending portion of said motor shaft to said impeller shaft; a fan compartment above said motor compartment; a fan in said fan compartment; means for transmitting power from the upwardly extending portion of said motor shaft to said fan; means for admitting air from the exterior of said machine to said motor compartment; a passage between said motor compartment and said fan compartment for transferring air from said motor compartment to said fan compartment; a first opening between said fan compartment and said tank, above the water line therein; and a second opening in said fan compartment opening to the atmosphere.

3. A dishwashing machine comprising: a tank; means for supporting dishes in said tank; a motor compartment in one extremity of said tank; a vertically mounted motor in said motor compartment having a motor shaft extending upwardly and downwardly therefrom; an impeller in said tank; an impeller shaft extending from said impeller through the bottom of said tank; means for transmitting power from the downwardly extending portion of said motor shaft to said impeller shaft; a fan compartment above said motor compartment; a fan in said fan compartment; means for transmitting power from the upwardly extending portion of said motor shaft to said fan; means for admitting air from the exterior of said machine to said motor compartment; a passage between said motor compartment and said fan compartment for transferring air from said motor compartment to said fan compartment; a first opening between said fan compartment and said tank, above the water line therein; a second opening in said fan compartment opening to the atmosphere; and a composite valve mechanism for alternately and simultaneously opening and closing said first and second openings when desired.

4. A dishwashing machine comprising: a dish receiving tank; an impeller mounted in the bottom of said tank; a motor chamber in the side of said tank; a motor plate closing the outer face of said motor chamber; means for carrying a motor on said motor plate, said motor having a higher elevation than said impeller; and means for communicating the power of said motor to said impeller.

5. A dishwashing machine comprising: a dish receiving tank; an impeller mounted in the bottom of said tank; a motor chamber in the side of said tank; a motor plate closing the face of said motor chamber; a motor support extending inwardly from said motor plate; a motor support extending by, and arranged to move horizontally on, said motor support; a belt arranged to communicate the power of said motor to said impeller; and means for urging said motor along said motor support to maintain said belt taut.

6. A dishwashing machine comprising: a dish receiving tank; an impeller mounted in said tank; a motor chamber extending into a side of said tank and open to the exterior thereof; a plate closing the open side of said chamber; a motor carried by said plate within said chamber; and means for communicating the power of said motor to said impeller.
7. In a dishwashing machine, a dishwashing tank; a motor compartment formed in said tank above the bottom thereof; a motor mounted in said motor compartment; a fan operated by said motor to draw air into said motor compartment; and a valve between said motor compartment and the interior of said tank so as to admit air from said compartment into said tank when desired; and a second valve between said compartment and the exterior of said tank, said two valves being interconnected so that when one opens the other will close.
8. In a dishwashing machine, a dishwashing tank; a motor compartment formed in said tank above the bottom thereof; a fan arranged to draw air into said motor compartment; a valve between said motor compartment and said tank so as to admit air from said compartment into said tank when desired; and a second valve positioned to control the discharge of air from said compartment to the exterior of said tank when desired.
9. In a dishwashing machine, a dish receiving tank; a motor compartment in said tank, said compartment opening at one of its sides through one wall of said tank and through the bottom thereof; a partition surrounding the remainder of said compartment and the top thereof and separating said compartment from said tank; a removable plate closing the open side of said compartment; a motor mounted on said plate; an impeller in said tank adjacent said partition; and means for transmitting the power of said motor to said impeller.
10. In a dishwashing machine, a dish receiving tank; a motor compartment in said tank, said compartment opening at one of its sides through one wall of said tank and through the bottom thereof; a partition surrounding the remainder of said compartment and the top thereof and separating said compartment from said tank; an outer wall closing the open side of said motor compartment; a valve seat in said outer wall; a valve seat in said partition; a valve for each of said seats; a connection between said valves so that as one opens the other will close; means for operating said valves; and a motor in said compartment arranged to drive an impeller in said tank.
11. In a dishwashing machine, a dish receiving tank; a motor compartment in said tank, said compartment opening at one of its sides through one wall of said tank and through the bottom thereof; a partition surrounding the remainder of said compartment and the top thereof and separating said compartment from said tank; an outer wall closing the open side of said motor compartment; a valve seat in said outer wall; a valve seat in said partition; a valve for each of said seats; a connection between said valves so that as one opens the other will close; means for operating said valves; a motor in said compartment arranged to drive an impeller in said tank; and a heater mounted on said motor between said valves.
12. In a dishwasher, a tank; a discharge con-
- duit for draining said tank; an air heater; a valve for admitting heated air from said heater to said tank; a second valve for opening said discharge conduit; a valve operating mechanism for said valves acting to open said second valve before it can open said first valve and to maintain the second valve open so long as the first valve is open.
13. A dishwashing machine having a tank; an impeller mounted on the bottom of said tank adjacent one end thereof; an indented compartment formed in the latter end of said tank, the inner wall of said compartment being positioned relatively close to said impeller; a shaft extending from said impeller through the bottom of said tank; a motor in said compartment with its shaft extending below the bottom of said tank; and a belt transmitting power from said motor to said impeller shaft.
14. A dishwashing machine comprising: a tank; an air heating compartment in one side of said tank; a first valve opening from said air heating compartment to said tank; a second valve opening from said compartment to the exterior of said tank; a sump tube for draining said tank; a valve for closing said sump tube; and means for controlling all of said valves so that said first valve will open when said second valve closes and vice versa; and so that said sump valve can not be closed until said first valve is closed.
15. A dishwashing machine comprising: a tank; an air heating compartment in one side of said tank; a first valve opening from said air heating compartment to said tank; a second valve opening from said compartment to the exterior of said tank; a sump tube for draining said tank; a sump valve for closing said sump tube; and means for controlling all of said valves so that said first valve will open when said second valve closes and vice versa; and so that said sump valve can not be closed until said first valve is closed, said latter means comprising: a lever carrying said sump valve; an arm for swinging said lever to position said sump valve over said sump tube, said arm being positioned so as to contact said second valve and hold said first and second valves in the opened and closed position respectively, while said sump valve is in the open position.
16. A dishwashing machine comprising: a tank; an air heating compartment in one side of said tank; a first valve opening from said air heating compartment to said tank; a second valve opening from said compartment to the exterior of said tank; a sump tube for draining said tank; a sump valve for closing said sump tube; and means for controlling all of said valves so that said first valve will open when said second valve closes and vice versa; and so that said sump valve can not be closed until said first valve is closed, said latter means comprising: a lever carrying said sump valve; an arm for swinging said lever to position said sump valve over said sump tube, said arm being positioned so as to contact said second valve to bring said first and second valves to the opened and closed position respectively after said sump valve is opened; and a locking device for engaging said arm to simultaneously hold said sump valve in the open position and said first and second valves in the open and closed positions, respectively.

HAROLD G. DAVIS.
